UNITED STATES PATENT OFFICE

99,763

DESIGN FOR A BOTTLE

Joseph M. Sansby, St. Paul, Minn.

Application January 25, 1936, Serial No. 60,801

Term of patent 14 years

To all whom it may concern:

Be it known that I, Joseph M. Sansby, a citizen of the United States, residing in the city of St. Paul, county of Ramsey, and State of Minnesota, have invented a new, original, and ornamental Design for a Bottle, of which the following is a specification, reference being had to the accompanying drawing forming a part hereof.

The single figure of the drawing is a front

elevation of a bottle showing my new design. The dominant feature of the design consists in the annular flanges projecting, one above the other, near the mouth or opening in the top of the bottle.

I claim:

The ornamental design for a bottle substantially as shown and described.

JOSEPH M. SANSBY.
